UNITED STATES PATENT OFFICE.

CHARLES H. RIPPL, OF CLEVELAND, OHIO, ASSIGNOR TO THE ELECTRIC CONTROLLER & MANUFACTURING COMPANY, OF CLEVELAND, OHIO, A CORPORATION OF OHIO.

OVERLOAD DEVICE.

Application filed December 14, 1921. Serial No. 522,231.

To all whom it may concern:

Be it known that I, CHARLES H. RIPPL, a citizen of the United States, residing at Cleveland, in the county of Cuyahoga and State of Ohio, have invented new and useful Improvements in Overload Devices, of which the following is a specification.

My invention relates to overload devices for electric systems which employ one or 10 more heat-expansive devices to cause the source of current supply to be disconnected from an electric motor or other translating device upon the existence of overloads having certain characteristics.

15 It is the principal object of this invention to provide an induction or other motor or its equivalent with one or more heat-expansive devices which will permit a normal heavy overload, such as occurs during the 20 starting of an induction motor, for example, to persist for a definite period, but will cause the current supply to be cut off if the overload persists beyond that period; which will interrupt the current supply immediately 25 upon the occurrence of an abnormally large overload which might destroy or damage the motor or its equivalent; and which will interrupt the current supply upon the persistence of smaller overloads for periods 30 whose lengths depend upon the sizes of the overloads.

While this invention may be used with various types of electrical systems and devices, I have shown it as a modification in 35 the system shown and described in the application of Homer E. Frost, Serial Number 488,990, filed August 1, 1921.

On the accompanying drawings, Fig. 1 is a side elevation of an overload device embodying the principles of my invention; Fig. 2, a bottom plan view of Fig. 1 with some of the parts omitted; Fig. 3, a view of the upper part of Fig. 1; Fig. 4, a sectional detail showing the rear member of 45 the tripping device; Fig. 5, an enlarged detail looking at the right hand of Fig. 3; Fig. 6, a detail of the tripping mechanism in the position in which it is when the circuit is open; Fig. 7, a diagrammatic view 50 of the circuit which may accompany my device; and Fig. 8, a diagram showing the efficiency of my invention.

On the drawings 1 indicates an insulating base composed of slate, for example. 2 and

3 are heat-expansive wires severally connected at one end to the metal blocks 6 and 7 seated in the respective forks 4 and 5 secured to the base 1. The blocks are adjustably held in the forks by the nuts 8 and 9 which bear on the outside edges of the forks. 55 The remaining ends of the wires 2 and 3 are insulated from each other and respectively connected to the shorter ends of the levers 10 and 11 which are insulated from the wires and pivoted on the pin and pivot 60 12 supported by the base 1. Each lever is composed of an outer member 13 and an inner member 14 connected together at their upper ends by a pin 15. To the pin 15 the wires 2 and 3 are respectively attached. 65 The levers 10 and 11 have inwardly projecting tripping fingers 16 and 17, respectively, formed by projections from their members 13 and 14. The projections of each pair of members are connected together by a spacing pin 18. The members 13 of the levers have below the projections 16 and 17 holes to loosely receive the end necks 19 of the equalizing pin or bar 20, which has central 70 between the necks 19 the neck 21 to which one end of the operating spring 22 is attached, the other end thereof being connected to the post 23 secured to the base 1. 75

24 is a switch-tripping lever comprising the back member 25 and the front member 26, both pivoted on the pivot 27 secured to the base 1. The members are connected together by the pin 28. The lower end of the member 25 is engaged by the spacing pin 18 of the lever 11, and the lower end of the lever member 26 is engaged by the spacing pin 18 of the lever 10, as shown best in Fig. 5. A switch-reset spring 29 tends to keep the lower ends of the members 25 and 26 in contact with the fingers 16 and 17. The upper end of the member 25 has the fork members 30 and 31, between which is the fixed post 32 acting as a stop for the fork members and as a support for the bell crank lever 33 pivoted on the outer end thereof, and having the 85 arms 34 and 35. An overthrow spring 36 connects the arm 34 to the upper end of the member 26, the spring lying to the right of the pivot post 32 when the arm 35 is horizontal. The arm 35 is connected by the link 90 of insulating material 36 to the free end of the lever 37 carried by the pivot 38 below the link. The pivot 39, which connects the 95 100 105

link to the lever 37, also carries the rocking contact 40, having its upper end arranged to engage the fixed contact or post 41 when the link and the arm (which are toggle-members) are in a substantially straight line, as shown on Fig. 1. The lower end of the lever is connected to the spring 42 which allows the contact 40 to have a wiping action on the contact 41. The contact 41 is connected by the lead 45 to the terminal 46. The lead 43 connects 38 to 44.

The end of the wire 2 connected to the block 6 is connected by the wire 48 to the terminal 57 on the base, and the end thereof connected to the lever 10 is electrically connected to one end of the coil 77 which is wrapped around the wire 2. Between the wire 2 and the coil 77 is a tube or sheath 78 composed of asbestos or other material. The remaining end of the coil is connected to the terminal 56 by the wire 47. Similarly, the wire 3 is provided with the coil 79 which is separated from the wire 3 by the tube or sheath 80, the ends of the wire and coil not joined to each other being connected to the terminals 60 and 59 by the wires 51 and 50, respectively.

Referring now to Fig. 7, the terminals 56 and 59 are connected to the two terminals 63 and 64 of the alternating current motor 65. The terminals 57 and 60 are connected to the movable switch members 66 and 67 of the switch 68. The third motor terminal 69 is connected to the movable switch member 70. The said switch members are pivotally connected to the operating bar 71, actuated by the switch-operating winding 72 to close the switch members 66, 67 and 70 on their fixed contacts 73, 74 and 75, and actuated by the spring 76 to open the said switch members when the winding 72 is de-energized. The contacts 73, 74 and 75 are connected to the source of alternating current supply by the supply wires 77', 78' and 79'. The winding 72 is connected in the circuit of the neutral contact 75 and in one of the outer wires, as 77', though the hand switch 80' and the parts 37, 38, 40 and 41, as shown in Fig. 7.

On Fig. 8 the equalizing pin 20 is represented as applied directly to the wires 2 and 3 at the points *a* and *b*, these indicating the position of the equalizer when the wires 2 and 3 are cold. The corresponding point of application of the spring 22 is indicated by the letter *c*. *a'* and *b'* indicate the position of the equalizing pin 20 when both the wires 2 and 3 become heated and stretch equally under the pull of the spring 22 until the levers 10 and 11 jointly cause the tripping lever 24 to open the contacts 40 and 41. When the equalizing pin 20 takes the position *a'*—*b'*, the point of application of the spring 22 is at *c'*. If the circuit of one of the wires, as 2, has been interrupted, the

equalizing pin will take the diagonal position *a*—*b'*, the point of application of the spring 22 being at *c''*.

Let it be assumed that the spring 22 exerts a pull of 15 lbs. at the point *c*. Then the pull thereof on the points *a* and *b* will be 7.5 lbs. each. Assume that, when the equalizing pin is at the position *a'*—*b'*, the pull of the spring has been reduced to 6 lbs. Then the pull at *a'* and *b'* will be reduced to 3 lbs. each. If the wire 2 is out of circuit, the point *a* will remain stationary while the point *b* will move to *b'*, the point *c* moving to *c''*, at which point the spring exerts a pull of only 10.5 lbs. divided between the points *a* and *b'*. The pull at *b'* will be somewhat in excess of 5.25 lbs., owing to the movement of the point *c''* of the application of the spring 22 slightly toward the point *b'*. The necks of the equalizing pin 20 cause a readjustment of the points of application when the bar moves from the position *a*—*b* to the diagonal position *a'*—*b'*, so that the power of the spring on the point *b'* is greater than on the point *a*. Thus, the spring which exerts a pull of only 3 lbs. on each wire when both wires are equally heated, exerts a pull of more than 5.25 lbs. on one heated wire, as 3, when the other wire, as 2, is open circuited. This means that the heated wire 3 is stretched sufficiently to trip the switch contact 40 before the wire 3 is heated to such a high temperature as would have been required if both wires were heated equally. If separate springs were employed, each pulling 7.5 lbs. at the points *a* and *b*, and the wire 2 was out of circuit, the spring acting on the point *a* would still exert a pull of 7.5 lbs. while the spring acting on the point *b'* would exert a pull of 3 lbs., a loss of 2.25 lbs. over the pull exerted at the point *b'* when only one spring is pulling at the point *c''*.

Referring particularly to Fig. 7, if the switch 80' is closed, the single phase current in the winding 72 will cause the switches 66, 67 and 70 to engage the contacts 73, 74 and 75, thereby connecting the neutral wire 79' to the motor terminal 69, while the outer wires 77' and 78' are connected to the remaining motor terminals 63 and 64 through the windings 77 and 79 and the two wires 2 and 3. When the contacts 40 and 41 are opened, the winding 72 is de-energized, permitting the spring 76 to open the switches 66, 67 and 70 and cause the motor 65 to stop.

As the upper end of the lever 24 is moved to the left in Fig. 1 by the action of the lever 10 or the lever 11 or both, the spring 36 passes from the right side of the fulcrum 32 of the lever 33 to the left side thereof, thereby causing the latter to move quickly from the position shown in Fig. 1 to that shown in Fig. 6 where the toggle members

35, 36, have pulled the lever 37 to the left enough to open the contacts 40 and 41.

So far the operation of my invention has been given without reference to the functions of the coils 77 and 79 and the tubes or sheaths 78 and 80. The wires 2 and 3 have larger cross-areas than the wires of which the coils are made. The wires 2 and 3 are affected in their degrees or amounts of expansion by heat due to current therein and also by heat transmitted from the coils through the tubes 78 and 80, if the latter are employed. The difference between the cross-areas of the wires 2 and 3 and cross-areas of the wires in the coils 77 and 79 may be compensated in whole or part by making the wires 2 and 3 of a material having a lower specific resistance than the wires of the coils. The time required for the coils to heat the wires 2 and 3 to a definite temperature is controlled by the thickness of the wall of the tubes 78 and 80 and the materials of which they are made. To increase the time element the walls of the tubes are made 25 thicker or of a poorer conductor of heat.

In starting an induction motor of the squirrel-cage type, it may be necessary to draw from three to five times full load current for three to ten seconds. The wires 2 and 3 are selected so they will not expand enough to cause the contacts 40 and 41 to be opened under these conditions. The wires of the coils are selected so that they will not be damaged and the tubes 78 and 80 are selected so that they will not transmit enough heat to expand the wires 2 and 3 to the tripping point. If the starting current should persist more than the predetermined number of seconds, the wires 2 and 3 will become 40 heated by the coils so as to cause the contacts 40 and 41 to open. It is clear that even with smaller overloads than the said normal starting overloads, the coils will, if sufficient time has elapsed, heat the wires 2 and 3 sufficiently to cause the supply circuit to be opened. As the tubes 78 and 80 retard the flow of heat to the wires 2 and 3, the coils and the wires 2 and 3 would burn out on a sufficiently high current, if provision 45 was not made against it. This provision consists in the present instance in making the wires 2 and 3 sufficiently small to cause them to expand enough by the current therein to trip the circuit breaker before the 50 wires of the coils, or the wires can be damaged.

It is manifestly impossible to state the proportionate correlation of the three functional elements, the expansive wires, the enveloping coils and the intermediate tubes or sheaths. Those skilled in the art can readily determine the proper characteristics of these elements for the particular installations desired.

55 I have shown my invention in connection

with a three-wire alternating current system, but it is evident that it is applicable to other multiphase systems, and to various other arrangements.

While I have described the expansive wire 70 as having a larger cross-area or a higher specific resistance than the wire of the coil, I may for some purposes make the expansive wire with a smaller cross-area or a lower specific resistance than the wire of the coil. 75

I claim:

1. In an overload device for an electric circuit, a switch for controlling the circuit, an expansive wire electrically connected to the circuit for controlling the switch, a coil electrically connected to the circuit and arranged to transmit heat to the wire, the thermal capacity per linear unit of the expansive wire and of the wire of the coil being so proportioned that, when current 80 above a predetermined value traverses the expansive wire and coil, the former will effect the operation of the switch without overheating the coil and, when current above a predetermined lower value traverses the 85 expansive wire and coil, the coil will transmit sufficient heat to the expansive wire to effect the operation of the switch before the coil becomes overheated.

2. In an overload device for an electric 95 circuit, a switch for controlling the circuit, an expansive wire electrically connected to the circuit for controlling the switch, a coil electrically connected to the circuit and arranged to transmit heat to the wire, an insulation between the expansive wire and the coil, the insulation having such thickness, and the thermal capacity per linear unit of the expansive wire and of the wire of the coil being so proportioned that, when current 100 above a predetermined value traverses the expansive wire and coil, the former will effect the operation of the switch without overheating the coil and, when current above a predetermined lower value traverses the 105 expansive wire and coil, the coil will transmit sufficient heat to the expansive wire to effect the operation of the switch before the coil becomes overheated.

3. In a circuit, a heat expansive wire for 115 controlling the circuit, and a heating coil connected thereto and arranged to heat the wire, the thermal capacities per linear unit of the expansive wire and the conductor of the coil being so proportioned that the expansion of the wire effective to control the circuit is due to the heat transmitted to the wire by the coil when the current in the circuit exceeds a predetermined value and is due to the heating of the wire by the current 120 therein when the current exceeds a second predetermined value.

Signed at Cleveland, Ohio, this 7th day of Dec., 1921.

CHARLES H. RIPPL.
